UNITED STATES PATENT OFFICE.

ROBERT SPURGIN, OF CHICAGO, ILLINOIS.

COIN-WRAPPER.

No. 831,115.

Specification of Letters Patent.

Patented Sept. 18, 1906.

Application filed February 23, 1904. Serial No. 194,780.

To all whom it may concern:

Be it known that I, ROBERT SPURGIN, a citizen of the United States, residing at Chicago, in the county of Cook and State of Illinois, have invented a new and useful Coin-Wrapper, of which the following is a specification.

The object of my invention is to provide a printed coin-wrapper to be used either with a 10 gummed edge or without, which when used upon a rouleau of coin will denote the total value, as well as the denomination of the coin contained therein, without the necessity of turning or even touching the rouleau in any 15 case, thus serving the double useful purpose of saving time and labor and minimizing the danger of errors and loss in paying out or receiving wrapped coin. It is the experience of bank-tellers, cashiers, and others who are 20 accustomed to handling rouleaus of coin that the natural tendency of such shaped packages often is, especially when hastily laid down, to roll over and over, being cylindrical. Therefore in the case of the printed 25 coin-wrappers heretofore commonly in use of which I have knowledge it is entirely a matter of chance whether the printed designation of their contents can be seen by one as the rouleau lies before him or not, for the 30 reason that it may be on the side of the rolled package opposite to his point of view. The necessity of handling the rouleau in many cases to examine its label, and thus remove any doubt as to its value on account of the 35 similarity in size between some denominations of coin, such particularly as one-cent and five-cent pieces and five-cent and twenty-five-cent pieces, is therefore apparent.

In the drawings, Figure 1 represents a 40 coin-wrapper for wrapping two dollars in five-cent pieces; *a a*, a direct column of main designations; *b b*, an inverted column of main designations; *c c c c*, marginal rows of designations; *d d*, separating-lines between the face and tuck-margins of the coin-wrapper; *e e*, tuck-margins; *f*, face of coin-wrapper. Fig. 2 represents a rouleau of two dollars in five-cent pieces.

A more particular description of my invention is as follows: My improved coin-wrapper consists of a sheet of paper of a size suited to the denomination of coin to be wrapped and the rouleau to be made up, on which printed direct designations indicating the 50 total amount and denomination of the rouleau are repeated at regular intervals in a ver-

tical column, on preferably the right side of the sheet, Fig. 1, *a a*, and in a similar inverted vertical column, on preferably the left side, Fig. 1, *b b*, each contiguous to the tuck-margin of the wrapper on either side, Fig. 1, *e e*. On each of the tuck-margins *e e*, which when the rouleau is complete form the tuck for both ends of the rolled package, Figs. 1 and 2, *e e*, a row of designations of the total amount 55 of coin to be contained likewise appear separated by regular intervals, the designations being abbreviated, Fig. 1, *c c c c*, and being set at right angles to the separating-lines between the face *f* of the coin-wrapper and the 60 tuck-margins *e e*, their bases toward the edges of the sheet. The designations in all the columns and rows on one wrapper correspond as to the amount to be contained. I preferably employ five designations of value for the direct and inverted columns *a a b b* and seven 65 designations of value for the marginal rows *c c c c* for each of the several sizes of coin-wrappers required, the intervals being relatively alike for the different sizes. I preferably 70 so arrange the inner columns of designations *a a b b* that the amount of a rouleau in dollars or cents in one column will appear on the face *f* of a roll of coin directly opposite the denominational description of the coin 75 contained therein in the other, Figs. 1 and 2, *a a b b*. I preferably make the two columns and two rows of printed designations coextensive with the length of the sheet in order that the coin-wrapper may be used with 80 exactly the same result whether starting at one end or the other in wrapping the rouleau, which action when ungummed coin-wrappers are used will be merely a matter of choice or 85 convenience on the part of the user. I preferably 90 place the direct and inverted columns *a a b b* contiguous to the tuck-margins of the coin-wrapper *e e* rather than nearer the middle in order that ample clear unbroken space 95 sufficient for making any desired notations 100 or imprint, such as a date or name, may be left for that purpose on the face of a rouleau *f*.

The effect of the repetition and arrangement of the designations as described is to make always certain the appearance at what 105 may chance to be at the time the right-hand side of a rouleau when lying horizontal and sufficiently in view a direct printed designation of the contents both numeric and descriptive, as but two designations in either 110 column are hidden in wrapping, or if the rouleau be so placed that only the flat trans-

verse part is in view one at least of the designations on the tuck margin is certain to be clearly in view, even without care on the part of the user in tucking, to produce that result, Fig. 2, *c e*.

I am aware that plural direct and inverted columnated designations have been used before in a contracted form in a labeling strap or band for flat rectangular packages of 10 per currency for the purpose of indicating the value of such packages on their perpendicular edges, but not in coin-wrappers intended to envelop and label cylindrical packages of coin. I do not, therefore, claim the principle 15 of direct and inverted indicia, Fig. 1, *a a b b*, broadly as new; but

What I do claim, and desire to have secured to me by Letters Patent, is—

A coin-wrapper for cylindrical packages of

coin, comprising a sheet bearing intermediate 20 columns of repeated direct and inverted value designations adapted for display on the cylindrical surface of the package, and outer rows of like designations parallel with but struck at right angles to said intermediate 25 columns of designations adapted for display on the folded ends of the package, at least one of said designations being visible in direct form from any point of view in any position of the package, substantially as described. 30

In testimony whereof I have signed my name to this specification in the presence of two subscribing witnesses.

ROBERT SPURGIN.
